UNITED STATES PATENT OFFICE.

JOHN E. MITCHELL, OF ST. LOUIS, MISSOURI.

BOLL-BREAKING AND COTTON-SEPARATING MACHINE.

Application filed February 14, 1927. Serial No. 167,974.

This invention relates to certain new and useful improvements in boll breaking and cotton separating machines, and has for its general object to improve the general arrangement and operation of parts characteristic of machines of this type heretofore invented by me. My invention is concerned particularly with improvements in the machines of my prior Patents No. 1,030,913 and No. 1,322,927.

The elements or working parts of the machine of the present invention are substantially the same as those shown in my prior patents referred to, but the arrangement and operation of the parts are such as to accomplish entirely different results, or rather, improved results, and particularly in the direction of so co-ordinating the operations of the breaker cylinder, saw cylinder, and kicker roll, that a great improvement in the quantitative separation of cotton from the bolls and mixed cotton and hulls acted on by the saw cylinder results.

In order that the advantages of the present embodiment of my invention may be better understood, I will first describe the same in detail and then refer to the machines of my prior patents and point out the advantages in the operation of the former over the latter.

Referring first to the drawing, the view illustrates in cross-section a machine constructed and arranged according to my invention.

In this drawing, the numeral 1 indicates generally, the casing enclosing the moving parts and provided on its upper side with an inlet or hopper 2 in which are located feed rollers 3, 4 arranged to rotate toward each other, or in opposite directions. Below these feed rollers there is mounted a rotatable breaking cylinder 5 having beater arms 6 pivotally mounted thereon and adapted to be rotated in the direction shown by the arrow. To the right of the breaking cylinder, as shown in the drawing, there is rotatably mounted a kicker roll 7 adapted to move in the direction shown by the arrow thereon and in functional relation to the periphery of a saw cylinder 8 which is adapted to be rotated in the direction shown by the arrow. The breaker cylinder is mounted in a chamber the lower side of which is formed by an inclined hullboard 9 the lower end of which terminates at a suitable distance from the periphery of the saw cylinder 8 to provide an outlet 10 for the escape of hulls and trash past the saw

cylinder. Such hulls and trash pass into a trough 11 in which is mounted a worm conveyor 12 which continuously removes the hulls and trash deposited in the trough from the machine. Located to the right and below the saw cylinder 8 is a doffer 13 adapted to rotate in the direction shown by the arrow and operating to continuously remove cotton carried around by the teeth of the saw cylinder and discharge it out of the machine. To the right of the breaker cylinder 5 and above the kicker roll 7 is an inclined guard or deflecting board 14 which, as shown, has its lower end located immediately above the kicker roll and its upper end extending well above the surface of the breaker cylinder, and in effect, being substantially tangential to the circular path described by the outer ends of the beater arm 6. The provision or disposition of this deflector board is an important feature of the invention and its function will be set forth in the description of the operation to follow.

In operation, the breaker cylinder 5 rotating in the direction shown by the arrow, picks off the bolls containing the cotton that are forced into the machine by the feed rollers 3, 4, and after breaking, or partially breaking, the bolls, forces the mixed unbroken bolls, loose hulls and cotton down the inclined hullboard 9 into contact with the rotating saw cylinder 8. The loosened hulls and trash fall through the opening 10 defined by the bottom of the hullboard 9 and the face of the saw cylinder 8, and into the trough 11 where the conveyor 12 discharges same from the machine.

The balance of the cotton and hulls, with any remaining unbroken bolls, is carried up by the saw cylinder 8 to the kicker roll 7 which, rotating in the direction shown by the arrow, operates to knock the unbroken bolls and hulls separated from the cotton back into the breaker cylinder, or in other words, into the path of the beater arm 6, where they are subject to additional beating action of these members and are again carried around and thrown against the saw cylinder at the discharge opening 10 for the hulls. This operation of throwing unbroken bolls back into the breaker cylinder by the kicker roll 7 is repeated as often as is necessary for the bolls to be broken so that the cotton may be freed and the loosened hulls escape past the saw cylinder through the opening 10. In the meantime all cotton freed from the bolls to such an extent that it can be firmly engaged by the

teeth of the saw cylinder 8 is carried through beneath the kicker roll 7 and around to the doffer 13 which removes the cleaned cotton from the revolving saw cylinder and dis- 5 charges same from the machine.

As previously stated, an important feature of this invention is the provision of the deflecting board 14 against which hulls and unbroken bolls are thrown both by the rotation of the breaker cylinder 5 and the kicker roll 7, this deflecting board being arranged substantially as shown so that any hulls or unbroken bolls thrown against it by either of the two rotating members referred to will 10 be deflected back into the breaker cylinder; otherwise, a considerable portion of the hulls and trash would be carried around by the kicker roll 7 and through the space indicated by 15 and the lower edge of the deflecting board or other stationary part of the casing.

It may be pointed out in this connection that any longitudinal space, no matter how small, such as that shown at 15, and defined 25 by the rotating kicker roll on the one side and a stationary part on the other side, has very great capacity for carrying through hulls and trash or even cotton, and it is very important to deflect everything away from any point of 30 approach of the kicker roll to a stationary part of the machine. It is necessary, of course, that the kicker roll should rotate in proximity to such a fixed part, acting as a guard, as otherwise unopened bolls, hulls and 35 the like, would be thrown over the kicker roll by the breaker cylinder or else be carried over by the kicker roll itself and thus be carried out by the saw without having the cotton separated therefrom.

40 In order that the purpose and advantages of the present arrangement may be more clearly understood, particularly as distinguished from the prior patents referred to, I will refer briefly to the constructions of 45 these prior patents and point out wherein they fail to accomplish the results which it is the object of the present invention to secure.

50 In the first Mitchell Patent, No. 1,030,913, the kicker roll 15 cannot throw the unbroken bolls and hulls separated from the cotton back into the breaker cylinder by reason of the latter being located too high above the working chamber. This object was sought 55 to be overcome in the machine disclosed in the later Patent, No. 1,322,927, where the breaker cylinder was not only located at a lower point in relation to the other working members, but was rotated in the same direction as the saw cylinder and kicker roll, so 60 that unbroken bolls were easily kicked back by the kicker roll 12 into the breaker cylinder. This machine, however, proved to be unsatisfactory under certain conditions for the reason that it was necessary to provide the semi-

circular guard shown in the drawing, but not numbered, between the kicker roll and breaker cylinder, to prevent the breaker cylinder from throwing mixed cotton and hulls into contact with the kicker roll and having 70 the same carried over by the latter. It was further necessary to extend this guard very low or almost to the plane of the axis of the breaker cylinder. It was then found, in practice, in cases where the machines were 75 loaded heavily enough to bring about any congestion in the working chamber 10, that the kicker roll 12 carried a great deal of hulls and trash and some cotton through the space between the flights of the kicker roll and the bottom of the semi-circular guard referred to, the cotton and hulls being pinched and carried through at that point to such an extent as to destroy the practicability of the machine in all cases where it was necessary 80 to carry a heavy load.

In order to overcome the difficulties and objections to the machines disclosed in the two patents referred to, the breaker cylinder in the new invention has been located at 90 a lower point in relation to the other members than that it is shown to occupy in the earlier patent, and other parts constructed and arranged so that unbroken bolls and separated hulls can readily be thrown by the kicker 95 roll back into the breaker cylinder, these two rotating parts being so positioned with relation to each other and to the deflecting board 14 that hulls and unbroken bolls can be thrown by the roller into the breaker cylinder and 100 carried around by the latter without any danger of being carried over into the cleaned cotton by the kicker roll 7.

The difficulties encountered in machines constructed according to my Patent No. 105 1,322,927 have been overcome in the present invention by rotating the breaker cylinder in the opposite direction from that shown in said patent, or opposite to the rotation of the saw cylinder. This is made possible by the 110 use of the deflecting board 14 positioned substantially as shown, and also by the use of a much larger saw cylinder, which makes it possible for the breaker cylinder to discharge the cotton, hulls and unbroken bolls 115 against the lower portion of the saw cylinder while the breaker cylinder is running in the opposite direction. In other words, in the use of a small saw cylinder such as that shown in my Patent No. 1,322,927, it was necessary to run the breaker cylinder in the same direction as the saw cylinder in order to discharge the cotton, hulls and the like 120 against the lower portion of the saw cylinder, and at the same time provide a hull board 125 with pitch enough for the loosened hulls and trash to slide out.

The factors, therefore, of a breaker cylinder located in relatively close juxtaposition to the saw cylinder and kicker roll for di- 130

rect co-operation with these members and being rotated in a direction opposite to that of said kicker roll and saw cylinder, an inclined deflector board for receiving the impact of hulls and bolls thrown against it by the kicker roll and the breaker cylinder and directing said hulls and bolls back into the breaker cylinder, and the greatly enlarged size of the saw cylinder permitting the breaker cylinder to discharge the cotton and hulls and unbroken bolls against the lower portion thereof or at a point adjacent the outlet opening 10, are the distinguishing characteristics of the present invention as compared with the machines of my prior patents above referred to.

It will be understood, of course, that the principle of operation of the machine as herein set out is not dependent upon the exact size and location of the parts as illustrated, but at the same time, the arrangement shown, and the relative location and arrangement of the working parts, are substantially such as I have found in practice to yield the best results.

The size of the saw cylinder employed can only be stated in relative terms. By reference for example, to my Patent No. 1,322,927, it will be seen that the saw cylinder there shown has a diameter something less than one and one-quarter times that of the diameter of the kicker roll and a little more than one-half that of the diameter of the breaker cylinder. In the present case, the diameter of the saw cylinder is something more than three times that of the kicker roll and about twice that of the breaker cylinder, disregarding the beater arms. These proportions, of course, are not absolute but they will serve to give an idea of the greatly increased size of the saw cylinder used in the machine of the present invention as compared with that of the saw cylinder of either of the machines of my prior patents.

45 I claim:

1. In a boll breaking and cotton separating machine, in combination with a rotatable saw cylinder, a rotatable kicker roll co-operating therewith for knocking back bolls and hulls carried up by the cotton, a hull-board, the lower end of which defines the size of an escape opening for hulls past said saw cylinder, and a rotatable breaker cylinder positioned to receive and act upon bolls and hulls thrown out by the kicker roll and to discharge such bolls and hulls together with the mixture of bolls, hulls and cotton delivered to the machine, and acted upon by said breaker cylinder, directly onto the saw cylinder, said breaker cylinder being adapted to be rotated in a direction opposite to the direction of rotation of the saw cylinder and in juxtaposition to said hull-board and downwardly as respects its side adjacent to said hull-board and in a direction opposite to the direction of rotation of the saw cylinder.

65 2. In a boll breaking and cotton separating

machine, in combination with a rotatable saw cylinder, a rotatable kicker roll co-operating therewith for knocking back bolls and hulls carried up by the cotton, a rotatable breaker cylinder positioned to receive and act upon bolls and hulls thrown out by the kicker roll and to discharge such bolls and hulls together with the mixture of bolls, hulls and cotton delivered to the machine, and acted upon by said breaker cylinder, directly onto the saw cylinder, said breaker cylinder being adapted to be rotated in a direction opposite to the direction of rotation of the saw cylinder, and means for deflecting hulls and bolls thrown outward by said breaker cylinder and kicker roll back into the path of rotation of the breaker cylinder.

3. In a boll breaking and cotton separating machine, in combination with a rotatable saw cylinder, a rotatable kicker roll co-operating therewith for knocking back bolls and hulls carried up by the cotton, a rotatable breaker cylinder positioned to receive and act upon bolls and hulls thrown out by the kicker roll and to discharge such bolls and hulls together with the mixture of bolls, hulls and cotton delivered to the machine, and acted upon by said breaker cylinder, directly onto the saw cylinder, said breaker cylinder being adapted to be rotated in a direction opposite to the direction of rotation of the saw cylinder, and an inclined deflector board common to said kicker roll and breaker cylinder and positioned to receive the impact of hulls and bolls thrown against the same by either and to deflect them back into the path of the breaker cylinder.

4. In a boll breaking and cotton separating machine, in combination with a rotatable saw cylinder, a rotatable kicker roll co-operating therewith for knocking back bolls and hulls carried up by the cotton, a rotatable breaker cylinder positioned to receive and act upon bolls and hulls thrown out by the kicker roll and to discharge such bolls and hulls together with the mixture of bolls, hulls and cotton delivered to the machine, and acted upon by said breaker cylinder, directly onto the saw cylinder, said breaker cylinder being adapted to be rotated in a direction opposite to the direction of rotation of the saw cylinder, and a deflector board positioned substantially tangentially to the circles described by the breaker cylinder and kicker roll and positioned to receive the impact of hulls and bolls thrown outward by said breaker cylinder and kicker roll and to deflect the same back into the path of rotation of the breaker cylinder.

5. In a boll breaking and cotton separating machine, in combination with a rotatable saw cylinder, a rotatable kicker roll located over the same and co-operating therewith for knocking back bolls and hulls carried up by the cotton, a rotatable breaker cylinder located above said saw cylinder and to one

side of said kicker roll and positioned in juxtaposition to said members to receive and act upon bolls and hulls thrown out by the kicker roll and to discharge such bolls and hulls together with the mixture of bolls, hulls and cotton delivered to the machine, and acted upon by said breaker cylinder, directly onto the saw cylinder, said breaker cylinder being adapted to be rotated in a direction opposite to the direction of rotation of the saw cylinder, and deflecting means located above and common to said kicker roll and breaker cylinder and operating to receive the impact of hulls and bolls thrown against the same thereby and to deflect them back into the path of the breaker cylinder.

6. In a boll breaking and cotton separating machine, in combination with a rotatable breaker cylinder, saw cylinder and kicker roll arranged in unobstructed and co-operative relation to each other, the saw cylinder being of relatively large diameter as compared with the kicker roll, a hullboard extending beneath said breaker cylinder the lower end of which defines the size of an opening for hulls past said saw cylinder, said breaker cylinder being adapted to be rotated in a direction opposite to the direction of rotation of the saw cylinder and downwardly as respects its side adjacent said hullboard and positioned to discharge the mixed cotton, bolls and hulls acted upon by it directly upon the surface of said saw cylinder at a point adjacent said outlet opening, and deflecting

means common to said kicker roll and breaker cylinder for receiving the impact of hulls and bolls thrown against the same thereby and to deflect them back into the path of the breaker cylinder.

7. In a boll breaking and cotton separating machine, a casing providing a substantially enclosed space, a hullboard confining one side of said space, a rotatable breaker cylinder mounted in said space and rotating in juxtaposition to said hullboard and downwardly as respects its side adjacent said hullboard, a saw cylinder and a co-operating kicker roll substantially confining another portion of said space, the saw cylinder being located below the breaker cylinder and, with said kicker roll, having unobstructed relation to said breaker cylinder, whereby mixed bolls, cotton and hulls fed into the machine to be acted upon by said breaker cylinder will be discharged thereby directly onto the surface of said saw cylinder, and hulls and bolls knocked back by said kicker roll may be thrown into the path of movement of said breaker cylinder, and an inclined deflector board common to said kicker roll and breaker cylinder and positioned to receive the impact of hulls and bolls thrown against the same thereby and to deflect them back into the path of the breaker cylinder.

In testimony whereof, I have hereunto set my hand.

JOHN E. MITCHELL.
